UNITED STATES PATENT OFFICE.

JACOB J. PLANCO, OF NEW YORK, N. Y.

CIGAR-BOX.

1,031,466.

Specification of Letters Patent.

Patented July 2, 1912.

Application filed April 11, 1912. Serial No. 690,023.

To all whom it may concern:

Be it known that I, JACOB J. PLANCO, a citizen of the United States, and a resident of the city of New York, borough of Manhattan, in the county and State of New York, have invented a new and Improved Cigar-Box, of which the following is a full, clear, and exact description.

My invention relates to a cigar box, and 10 an object of my invention is to provide a box in which cigars of peculiar configuration may be packed in position separate from one another so as to prevent injury to the same.

A further object of my invention is to 15 provide a box in which the cigars are so arranged that they may be readily withdrawn.

I attain the above outlined objects by disposing within the box a separating member taking the form of the side of the cigars in 20 the box.

Reference is to be had to the accompanying drawings, forming a part of this specification, in which similar characters of reference indicate corresponding parts in all 25 the figures, and in which—

Figure 1 is a perspective view looking down upon a box containing a preferred embodiment of my invention; and Fig. 2 is a transverse sectional view taken on the line 30 2—2 of Fig. 1.

The box A is of the usual form of box of this character, and constructed of wood, pasteboard or other suitable material, having an inner paper lining B. In the drawing, the invention is shown in a case where it is desired to separate triangle-shaped cigars C, so that the sharp edges may not be broken in carrying the box with some of the cigars removed, or in withdrawing 35 the cigars from the box. In the drawing, the cigars are arranged with each alternate cigar resting on a face of the triangle, and each of the other cigars resting on an apex thereof.

40 The cigars arranged in a layer are separated by a separating strip D, the illustration showing two strips. The strip takes the form in this instance, of serrations, preferably having one end thereof E fastened to the box. This strip D is made up of a series of comparatively stiff sections connected to one another end to end, each two connected sections being of a length equal to and coinciding with the two sides of a triangular 45 cigar adapted to be embraced thereby. As illustrated, the cigars adapted to be packed

and carried in this box are of a form in cross section of an isosceles triangle, but I do not wish to be limited to the exact form thereof illustrated. It is preferable, however, in carrying out the spirit of this invention that each of said separator sections will substantially contact with the bottom and closed top of the box, whereby when the top is closed all of the separator sections 60 will be maintained in substantially the position indicated in the drawings, making it impossible for a cigar in any one of the triangular spaces to become displaced or damaged by jostling about, irrespective of 65 any of the other spaces. In other words, my box is particularly well adapted for carrying a quantity of cigars and using the same therefrom. Any of the cigars being left in the box after some of the cigars have 70 been used will be snugly held in place by the particular means herein specified. As shown in Fig. 2 particularly each of the separator sections meets both the bottom and the closed top at oblique angles, and since all of the 75 said sections are connected to one another end to end, it is an impossibility for any of the triangular spaces, even though empty, to become distorted when the box top is closed.

85 In place of a pair of members D, as shown in Fig. 1, it is, of course, to be understood that any number of these members may be substituted for the pair shown, or but one of the members may be used of a length 90 substantially equal to the length of the cigars.

Having thus described my invention, I claim as new and desire to secure by Letters Patent:

95 1. A box for holding cigars triangular in cross section, provided with a strip extending across the interior thereof and bent to form triangular spaces, whose apices are arranged alternately, whereby the cigars will 100 be held in the upper and lower spaces of the said strip.

105 2. The herein described box for cigars triangular in cross section, comprising a top and a bottom spaced apart a distance substantially equal to the altitude of said cigar triangle, and a strip extending across the interior of said box and comprising a series of stiff separator sections of equal length connected each to each, each of said sections 110 having a length equal to that of the side of the cigar and meeting the bottom and closed

top of the box at oblique angles, whereby
the strip will be maintained in position to
form a plurality of equal spaces, each space
being adapted to receive a single triangular
cigar and hold it in place irrespective of all
of the other spaces.

In testimony whereof I have signed my

name to this specification in the presence of
two subscribing witnesses.

JACOB J. PLANCO.
